UNITED STATES PATENT OFFICE.

ABRAHAM F. FIGGURES, OF WOMACK HILL, ALABAMA.

TRENCH-DIGGER.

1,366,253.

Specification of Letters Patent. Patented Jan. 18, 1921.

Application filed May 21, 1919. Serial No. 298,775.

To all whom it may concern:

Be it known that I, ABRAHAM F. FIGGURES, a citizen of the United States, residing at Womack Hill, in the county of Choctaw and State of Alabama, have invented certain new and useful Improvements in Trench-Diggers; and I do hereby declare the following to be a full, clear, and exact description of the invention, such as will enable others skilled in the art to which it appertains to make and use the same.

This invention relates to trench diggers and the primary object of the invention is to provide an improved machine for digging trenches, earth works and the like for military purposes.

Another object of the invention is to provide a tractor of the caterpillar type carrying a forwardly extending frame having means for digging a trench and for conveying the earth from the trench being dug to one side of the same, to form a breast work.

A further object of the invention is to provide an improved means for operatively connecting the endless conveyer belts with the tractor so as to use the power thereof for conveying the dirt from the trench being dug as well as motive purposes.

A still further object of the invention is to provide an improved mechanical trench digger of the above character, which is extremely efficient and durable in use, one that is simple and easy to manufacture, and one that can be placed upon the market at a reasonable cost.

With these and other objects in view, the invention consists in the novel construction, arrangement and formation of parts, as will be hereinafter more specifically described, claimed and illustrated in the accompanying drawings, forming a part thereof, in which—

Figure 1 is a side elevation of the improved device,

Fig. 2 is a top plan view of the same.

Fig. 3 is a front elevation of the same,

Fig. 4 is a detail plan view showing the means for operatively connecting the conveyer belts together,

Fig. 5 is a detail cross section taken on the line 5—5 of Fig. 2.

Referring to the drawings in detail, wherein similar reference characters designate corresponding parts throughout the several views, the numeral 1 generally indicates the improved trench digger which in-

cludes the tractor 2 of steam engine type. The tractor 2 includes the boiler 3, of the ordinary or any preferred construction, having the usual smoke stack 4 and fire box 5 and steam dome 6. The engine 7 is mounted upon the boiler and includes the usual cylinder 8, governor 9, piston rod 10, cross head 11, pitman 12 eccentrically connected to wheel 13 on the power shaft 14, which has connected thereto the usual fly wheel and pulley mechanisms 15 and 16. The drive shaft 13 has connected thereto the drive pinion 15' which is connected by the usual train of gears 17, with the bull wheels 18 which have teeth 19 formed on the periphery thereof for engaging the tractor or caterpillar belts 20 which extend around the same and the forward wheels 21, which are secured to the forward end of the boiler. The tractor is provided with the usual throttle levers 22 and other controlling mechanisms. The rear end of the tractor is provided with the usual cab 23 and fender 24 which may be connected to the tractor if so desired.

A frame 25 extends forwardly from the tractor and includes a pair of parallel spaced longitudinal side bars 26, which are bolted or otherwise secured to the boiler 3 of the tractor. The forward ends of side bars 26 are connected by a cross bar 27, which supports the swinging axle 28, which carries the supporting wheels 29. This axle may be connected to suitable steering means controlled from the cab of the tractor if so desired. The cross bar 27 supports the downwardly extending plow 30 which has its side edges bent up as at 31 and its forward end pointed as at 32 for facilitating the insertion thereof in the ground and the plowing of the ground.

A pair of shafts 33 and 34 are mounted adjacent the front and rear ends of the frame and extend transversely of the same and have keyed thereto the rollers 35 around which travels the longitudinally extending conveyer belt 36. The belt 36 is provided with a plurality of spaced flights 37 and this belt is adapted to convey the earth from the plow 30 to the rear end of the machine. As clearly shown in Fig. 1 of the drawings, the conveyer belt 36 ends short of the rear end of the frame and extends above the lateral conveyer belt 38 which extends upwardly from the frame and forms means for conveying the earth from the longitudinal con-

veyer to one side of the trench being dug, so as to form a breast work for the same. One of the longitudinally extending bars 26 supports the upwardly inclined parallel spaced laterally extending bars 39, the upper ends of which rotatably support the roller 40, and the opposite side bar carries a pair of depending brackets 41, which rotatably support a shaft 42, which has keyed thereto the roller 43. The conveyer belt 38 extends around the rollers 40 and 43 and has a plurality of flights 44 attached thereto. The longitudinally extending side bar 26 adjacent to the laterally extending arms 39 supports a guide roller 47, which engages the upper and lower runs of the belt 38 and divide the same into a horizontally disposed portion which lies directly in rear of and below the longitudinally extending conveyer belt 26 and an upwardly inclined run 48. A drive shaft 49 extends transversely across the frame 25 and is journaled in the longitudinally extending bars 26 directly in front of the rear roller 35 and this shaft has secured thereon a pinion 50, which engages with the pinion 51 carried by the rear roller. The shaft also carries a pulley 52, around which is trained the drive belt 16, extending from the pulley of the tractor. The shaft 49 carried by the side bars 26, is extended beyond one of the side bars and has keyed thereto the worm 54, which meshes with the worm-gear 55 keyed to the opposite end of the shaft 42, from which the pulley wheel 35 is carried. This forms effective means for driving the longitudinal and side conveyer belts.

From the foregoing description it can be seen that an improved mechanical trench 40 digger is provided, which will effectively dig and pile the earth on one side of the

trench and thus form an effective earth-work for military defense.

In practice, I have found that the form of my invention illustrated in the accompanying drawings and referred to in the above description, as the preferred embodiment, is the most efficient and practical; yet realizing the conditions concurrent with the adoption of my device will necessarily vary. I desire to emphasize that various minor changes in details of construction, proportion and arrangement of parts may be resorted to, when required without sacrificing any of the advantages of my invention as set forth.

What I claim as new is:

In combination, a tractor having a power take-off, a horizontally disposed conveyer frame secured to the front end of the tractor and extending forwardly thereof, an endless conveyer carried by said frame and terminating short of its rear end, an axle pivoted to the forward end of the frame, steering wheels journaled on said axle, an inclined plow secured to the frame in advance of the wheels and conveyer, an upwardly inclined and laterally extending conveyer frame secured to one of the side members of the first frame and adjacent the rear end thereof, a conveyer carried by the second frame and having its lowermost end disposed under the rear end of the first conveyer, and means driving the conveyers by the power take-off.

In testimony whereof I affix my signature in presence of two witnesses.

ABRAHAM F. FIGGURES.
